UNITED STATES PATENT OFFICE.

EDMUND F. SNYDER, OF BROOKLYN, NEW YORK.

DESIGN FOR A SPICE-CABINET.

SPECIFICATION forming part of Design No. 28,605, dated May 10, 1898.

Application filed October 23, 1897. Serial No. 656,217. Term of patent 7 years.

To all whom it may concern:

Be it known that I, EDMUND F. SNYDER, of Brooklyn, county of Kings, and State of New York, have invented and produced a new and original Design for a Spice-Cabinet, of which the following is a specification, reference being had to the accompanying drawings.

The essential feature of my design consists in a spice cabinet or box having rounded corners and provided with a flanged lid and an angular plate placed in the lid, as will be more fully described hereinafter.

In the accompanying drawings, Figure 1 is a perspective of a box or cabinet which embodies my design. Fig. 2 is a vertical cross-section of the same.

a represents a shallow box or cabinet having rounded corners and the lid *b*. This lid is provided with the flange *b*² upon its inner side, and extending parallel with the lower inner edge of this top *b* is an angular or bent plate *c*, provided with the lip *c'*.

Having thus described my invention, I claim—

A design for a spice-cabinet substantially as shown and described.

EDMUND F. SNYDER.
